UNITED STATES PATENT OFFICE.

WILLIAM WALKER STRONG, OF PITTSBURGH, PENNSYLVANIA.

DEVICE FOR DETECTING SUSPENDED MATTER IN GASES.

1,070,556.

Specification of Letters Patent.

Patented Aug. 19, 1913.

Application filed February 17, 1912, Serial No. 678,282. Renewed January 8, 1913. Serial No. 740,040.

To all whom it may concern:

Be it known that I, WILLIAM WALKER STRONG, a citizen of the United States, and a resident of Pittsburgh, in the county of Allegheny and State of Pennsylvania, have invented a new and useful Improvement in Devices for Detecting Suspended Matter in Gases, of which the following is a specification.

10 My invention relates to devices for detecting the presence of suspended matter and impurities in gases, more particularly for ascertaining the condition of smoke and fumes in smoke stacks, and it consists in the combinations, constructions and arrangements herein described and claimed.

An object of my invention is to provide a device in which a local circuit may be energized for the purpose of sounding an alarm, 20 automatically regulating the draft, or for any other purpose, whenever the gas has a certain amount of suspended matter present.

A further object of my invention is to provide an arrangement whereby the suspended 25 matter itself forms one of the means by which the energization of the local circuit is accomplished.

Other objects and advantages will appear in the following specification, and the novel 30 features of the invention will be particularly pointed out in the appended claims.

My invention is illustrated in the accompanying drawing, forming part of this application, in which—

35 Figure 1 is a diagrammatic view showing one embodiment of my invention; Fig. 2 is a modified form of the device; Fig. 3 is an enlarged view of the galvanometer - rheostat; and Fig. 4 is a detailed view showing the 40 rheostat contacts.

In carrying out my invention I provide a source of alternating current such as the generator G in Fig. 1. In circuit with this generator is the primary P of a transformer.

45 The secondary, S, of the transformer is connected by means of the wires 1 and 2 with the terminals 3 and 4 respectively, which are located inside of an exit flue or chimney 5, through which the smoke or gases are de- 50 signed to pass.

Disposed between the electrodes 3 and 4 are the electrodes 6 and 7. The former is connected by means of the wire 8 with a source of current G¹, and the electrode 7 is 55 connected by means of the wire 9 with an instrument 10 such as a bell, a relay, or other

electrical device, the latter being connected, in its turn, to one side of the generator G¹ by means of a wire 11.

From the foregoing description of the various parts of the device the operation thereof may be readily understood. The alternating current through the primary P of the transformer is stepped up by the secondary S until the voltage is relatively high, say 60 from 30,000 to 40,000 volts. Now the electrodes 3 and 4 are far enough apart so that, under ordinary conditions, there will be no 65 sparking between these electrodes. The terminals 6 and 7 which are in line with the electrodes 3 and 4, are separated, and since the generator G¹ is a comparatively low voltage 70 generator, say 110 volts, the instrument 10 will not be effective, since there will be no flow of current, owing to the break at electrodes 6—7. 75 Now when the space surrounding these electrodes 3, 4, 6 and 7, contains a sufficient quantity of suspended matter, as for instance, air containing smoke or other products of combustion, then it is found that 80 sparks will pass between the electrodes 3 and 4. The resistance between the terminals 6 and 7 is broken down during the time of the passage of the sparks between the electrodes 85 3 and 4, or in other words, conductivity between the terminals 6 and 7 is increased to such an extent that a current will flow through the local circuit containing the generator G¹ and the instrument 10 so as to operate the latter. As stated before, this 90 instrument may be an audible signal, or a visual signal, or a relay for effecting current connections to operate controlling apparatus (not shown).

In Fig. 2 I have shown a modification in which the electrodes 3 and 4 are the only ones which are located in the flue or chimney 5. In this modification a galvanometer-rheostat, or other suitable instrument, is disposed in a secondary circuit of which the 100 electrodes 3 and 4 form a part. The presence of suspended matter in the vicinity of the electrodes 3 and 4, as in the instance given above, will cause a variation of the flow of current in the secondary circuit. 105 This variation of current will cause the needle N of the galvanometer - rheostat R to swing, the deflection of the needle being dependent upon the amount of current. The deflection of the needle may in turn, cause an 110 increase or decrease of the flow of current in the local circuit of which the battery B and

the instrument D are parts. This control of the local circuit may be effected in many different ways. I have illustrated the same diagrammatically by showing the needle N of the galvanometer-rheostat bent downwardly so as to contact with the mercury M in the mercury cups C which form the terminals of the rheostat wires W and w.

It will be apparent that since the flow of current in the secondary circuit depends on the condition of the gases, *i. e.*, the amount of suspended matter, and since the movement of the galvanometer controls the amount of current flowing in the local circuit from battery B by wire 12 through the galvanometer-rheostat R, thence by wire 13 through the instrument D, and back to the local battery B by wire 14, the instrument D may be made to accurately register or record the condition of the gas at any given time, or it may be an automatic device for regulating the draft. The precise function of the instruments D and 10 in the examples given is not important as far as this invention is concerned, and these examples are merely given for the purpose of indicating some of the uses to which the local circuits which are energized in the manner described, may be put. The main object of the invention, as stated above, is to energize the local circuits by means of the suspended matter in the gases.

I am aware that various modifications based upon the same general principles might be made, but I consider as my own all such modifications as fairly fall within the spirit and scope of the invention.

I claim:

1. In a device for detecting the presence of suspended matter in gases, a flue or chimney for the passage of the gases, a pair of electrodes disposed within said flue, a source of high potential connected with said electrodes and forming a main circuit, the movement of the suspended matter past the electrodes serving to cause sparking between

the electrodes, a local circuit, and means actuated by the change in current in the main circuit for energizing the local circuit.

2. In a device for detecting the presence of suspended matter in gases, a flue or chimney for the passage of the gases, a pair of electrodes disposed within said flue, a main circuit including a source of current connected with said electrodes, the presence of suspended matter in the gases in the vicinity of the electrodes causing a change of current in the main circuit, a local circuit, and means actuated by the change of current in the main circuit for energizing the local circuit.

3. In a device for detecting the presence of suspended matter in gases, a flue or chimney for the passage of the gases, a pair of electrodes disposed within said flue, a pair of terminals disposed between said electrodes, a main circuit including a source of potential connected with said electrodes, a local circuit including a source of current, and a detecting instrument connected with said terminals, the presence of suspended matter in the gases in the vicinity of said electrodes serving to cause sparking between them whereby the resistance between the terminals is decreased to permit the passage of current in the local circuit.

4. In a device for detecting the presence of suspended matter in gases, a flue or chimney for the passage of the gases, a pair of electrodes disposed within said flue, a main circuit including a source of current connected with said electrodes, the presence of suspended matter in the gases in the vicinity of the electrodes causing a change of current in the main circuit, and a local circuit arranged to be energized by a change of current in the main circuit.

WILLIAM WALKER STRONG.
